UNITED STATES PATENT OFFICE.

ANDERSON TAYLOR, OF FAIRVILLE, MISSOURI.

IMPROVEMENT IN APPARATUS FOR LOADING WAGONS.

Specification forming part of Letters Patent No. 179,972, dated July 18, 1876; application filed June 20, 1876.

• *To all whom it may concern:*

Be it known that I, ANDERSON TAYLOR, of Fairville, in the county of Saline and State of Missouri, have invented a new and Improved Elevator, of which the following is a specification:

Figure 1 is a side elevation in section, taken on line *y y* in Fig. 2. Fig. 2 is a plan on line *x x* in Fig. 1.

Similar letters of reference indicate corresponding parts.

My invention relates to that class of elevators which are used to raise heavy articles for loading wagons; and it consists in a lever supported on suitable frame-work, to the shorter end of which a platform is suspended, and the longer end engages with a ratchet, the whole so arranged that a heavy article placed on the platform may be raised to the required height, when it will be retained by the ratchet.

A is a lever, having its fulcrum at *a a* in the posts *B B*. A platform, *C*, is suspended from a cross-bar, *c*, which is attached to the short end of the lever *A* by the side pieces *d*. Guides *e e* are attached to the platform *C*, and move in slots in the standards *D D*. Rollers *f f* are attached to the side pieces *d*,

which bear against the standards *D D*. A ratchet bar or standard, *E*, is placed in such a position as to engage with the long end of the lever *A*, which is beveled on the under side to fit the ratchet. A bar, *F*, is attached to the ratchet-bar *E* in such a way as to leave room between it and the ratchet-bar for the lever *A* and a spring, *g*, which is attached to the lever *A*, and bears against the bar *E*.

Any load placed on the platform *C* may be raised to the required height by forcing the long arm of the lever down. The spring *g* causes the lever *A* to engage with the ratchet-bar, retaining the load.

Having thus described my invention, I claim as new and desire to secure by Letters Patent—

1. The combination of the lever *A*, platform *C*, and ratchet-bar *E*, substantially as shown and described.

2. The combination of the guides *e e*, rollers *f f*, platform *C*, and standards *D D*, substantially as shown and described.

ANDERSON TAYLOR.
